UNITED STATES PATENT OFFICE.

CARL W. SAWYER, OF MARION, OHIO.

FILE-CASE.

No. 877,600.

Specification of Letters Patent.

Patented Jan. 28, 1908.

Application filed April 25, 1907. Serial No. 370,164.

To all whom it may concern:

Be it known that I, CARL W. SAWYER, a citizen of the United States, residing at Marion, in the county of Marion and State of Ohio, have invented certain new and useful Improvements in File-Cases, of which the following is a specification.

My invention relates to a file case or box particularly adapted for use in filing souvenir 10 postal cards and has for its object the provision of a device of this character constructed in such manner that a large or small number of cards may be held in a vertical position therein and cards of any given character 15 may be readily classified, the entire structure being constructed in such manner that it may be very cheaply made and ready access may be had to any desired card.

Further objects and advantages of the invention will be set forth in the detailed description which now follows.

In the accompanying drawing: Figure 1 is a perspective view of a file case or box constructed in accordance with the invention, 25 Fig. 2 is a longitudinal section through said box with the lid closed, Fig. 3 is a transverse section upon line $x-x$ of Fig. 2, and, Fig. 4 is a detail perspective view of one of the index cards.

Like numerals designate corresponding parts in all of the figures of the drawing.

Referring to the drawing, the numeral 5 designates the body of the file case or box. This case comprises a bottom 6, end walls 7 35 and a rear wall 8. The front wall 9 is hinged to the bottom 6 as at 10 by a fabric strip or hinge. A top 11 having a front flange 12 and end flanges 13, is hinged in the same manner at 14 to the rear wall 8. The end walls are cut out as at 15 and 16 for the 40 reception of the flanges 13, while the upper edge of the front wall is cut out as at 17 for the reception of the flange 12. The ends of the front wall are cut out as at 18 for the 45 reception of the front edges of the end walls 7. It will therefore be seen that all of the corners present unbroken and flush surfaces when the box is closed. A false bottom 19 has a 50 recess 20 formed in its underside and a slot 21 is formed through the upper wall of this recess.

A follower plate 22 which carries a horizontal flange 23 at its lower edge, is adapted to slide longitudinally of the box and to hold 55 any desired number of cards in a substantially vertical position. This flange 23 is

secured by a rivet 24 to a plate 25. The outer edges of this plate are turned over as at 26 and engage the edges of a spring plate 27, the head of the rivet bearing against the 60 spring plate and the tension of this spring holding the follower plate down against the upper face of the false bottom. The plates 25 and 27 are in effect tensioning devices and this tension may be adjusted as desired 65 by removing the false bottom and striking upon the head of the rivet to tighten said rivet and to consequently bind the spring plate 27 more firmly against the outer edges of the plate 25. The upward thrust of the 70 spring plate, forces the edges of the plate 25 more firmly into engagement with the undersides of the false bottom when this is done. This tension is sufficient to maintain the follower plate in any position to which it is 75 moved.

Index cards 28 which are adapted to receive any desired lettering such as the names of various States or countries, space the postal cards proper indicated at 29, from 80 each other, and provide means for classifying said cards in groups. The edges of the index cards 28 are diagonally cut away as at 30. It will therefore be seen that the edges of the post cards proper, may be readily 85 grasped.

I am aware that it has been customary in filing cases and boxes, to cut away portions of the index cards to render visible other index cards, but I am not aware that index 90 cards having their corners entirely cut away as illustrated in Fig. 4 to permit other cards to project from between them in the manner illustrated in Fig. 1, have ever been used. This structure of the index cards combined 95 with the front wall which is movable outwardly and downwardly, permits any desired post card to be readily withdrawn from its position.

From the foregoing description, it will be 100 seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims. 110

What I claim, is:

1. In a device of the character described,

the combination with a receptacle having a solid bottom, of a false bottom for said receptacle having a longitudinal slot formed therein, a follower block mounted to travel 5 over the upper face of said false bottom, a plate secured to said follower block having its edges inturned, a spring plate adapted to be engaged by the inturned edges of the first named plate, and a rivet which passes 10 through both of said plates and is carried by the follower block.

2. In a device of the character described, the combination with a receptacle having a solid bottom, of a false bottom for said receptacle, a follower block mounted to slide 15

over said false bottom, said false bottom having a slot formed therein, a follower block mounted to travel over the upper face of said false bottom, a plate secured to said follower block and having its edges inturned, a 20 spring plate adapted to be engaged by the inturned edges of said first named plate, and a member which passes through both of said plates and is carried by the follower block.

In testimony whereof I affix my signature 25 in presence of two witnesses.

CARL W. SAWYER.
